UNITED STATES PATENT OFFICE.

LÉON FERON, OF BRUSSELS, BELGIUM.

SKITTLE-GAME APPARATUS.

1,224,727.

Specification of Letters Patent.

Patented May 1, 1917.

Application filed August 1, 1914, Serial No. 854,544. Renewed September 22, 1916. Serial No. 121,695.

To all whom it may concern:

Be it known that I, LÉON FERON, a subject of the Belgian King, and resident of Brussels, Belgium, have invented certain new and useful Improvements in or Relating to Skittle-Game Apparatus, of which the following is a specification.

The present invention relates to skittle games of any kind and has for its object to provide a device which sets up and puts again in their relative places on the spot the various skittles after the latter have been upset by the players, said device being simple and accurate, easy to manufacture and cheap.

The novel device consists in connecting the skittles by means of fine ropes or the like with a board vertically slidable within a movable frame or slide. The slide moves in such a manner that the skittles, hanging below the board to which they are connected by the ropes, may be lowered on their required places on the table and are guided during such downward motion by means of corresponding guides provided on said slide.

The above improvements, and other minor ones, will be described with reference to the accompanying drawings, in which:

Figure 1 is a top plan view of a billiard table on which are disposed two games of skittles provided with the improved device.

Fig. 2 is a vertical, longitudinal section of same.

Fig. 3 is a detail, drawn at an enlarged scale, of the rear portion of the billiard table shown in Figs. 1 and 2.

Fig. 4 is a plane view of the lower face of the movable board.

Fig. 1 shows a billiard table on which are arranged two games of skittles. 1 is the table proper of the billiard or any like table on which are disposed the skittles 2 shown in Fig. 2 in their respective positions and connected by means of ropes 3 or the like to a board 4. This board is vertically movable and is guided by means of tubular guides 5 along vertical guide-bars 6 provided on the frame 7¹, 7², 7³ forming the slide. The board 4 is provided at its lower face with a plurality of hooks or the like fastening devices 14 to which are fastened the ends of the ropes 3. The board 7² forming the lower side of the guide is provided with holes registering with the hooks or the like 14 and through which extend the ropes 3 in such a manner that the skittles 2, raised with the

board 4, may be moved on the desired places when the slide is conveniently moved forward above the spot on which the skittles should be disposed. Said places correspond to the German game of skittles or to the bowling game or to any other kind of skittle game.

The up and downward motion of the board 4 in the frame is controlled by means of a cord 8 passing over pulleys 9 and the end of which is in reach of the players.

After one player raised the board 4 up to the upper side 7¹ of the slide by means of the cable 8, the slide is pulled toward the front, just above the spot where the skittles are disposed, (Fig. 2), after which a counterweight 10 or a spring or the like pulls back the frame to its normal position at the rear of the billiard table, so that the device does not interfere with the play.

The device works as follows:

When the skittles are arranged in their required position on the table, and the slide 7¹, 7², 7³ is in the rear of the frame 1; the board 4 is in its lowermost position and rests on the lower side 7² of the slide frame and the ropes 3 are in an inclined position.

For putting in position the fallen skittles at the end of a play, the board 4 is first raised so that the skittles assume the position shown in dotted lines in Fig. 3, then the device is pulled toward the front just above the spot where the skittles should be placed, after which the board 4 is carefully lowered so that the various skittles assume the required positions. When releasing the cord 8, the counterweight 10 pulls the frame 7¹, 7², 7³ back to its usual position at the rear (Fig. 2) and the board 4 slides downwardly.

Of course board 4 and frame 7¹ 7² 7³ may be operated independently from each other.

It may be understood that such a device may be applied to any kind of game of skittles without any risk of entanglement of the various ropes.

Having now fully described my said invention, what I claim and desire to secure by Letters Patent, is:

1. In a game apparatus, the combination of a frame provided with a track, horizontal guides at the rear of the frame, a frame slidably mounted in the horizontal guides, a plurality of skittles adapted to be supported on the track, means mounted in the slide frame for raising the skittles including a flexible connection, said flexible

connection also serving to draw the slide-
able frame forward after the skittles are
elevated, and means for drawing the slide-
able frame rearwardly to normal position,
5 the skittles falling from the sliding frame by
gravity when the flexible connection is re-
leased.

2. In a game apparatus, the combination
of a frame provided with a track, horizontal
10 guides at the rear of the frame, a frame slide-
ably mounted in the horizontal guides, a
plurality of skittles adapted to be supported
on the track, a vertically movable support
mounted in the sliding frame, flexible con-
15 nections between the skittles and the verti-
cally movable support, a guide on the slide-
able frame, a flexible connection attached to
the vertically movable support and passing
over the guide to raise the latter and the
20 skittles and to draw the sliding frame for-
wardly, and means for drawing the slide-
able frame rearwardly, the skittles and the verti-
cally movable support falling by gravity
when the flexible connection is released.

25 3. In a game apparatus, the combination
of a frame having a track, horizontal guides
near one end of the frame, a sliding frame
mounted in the guides, said sliding frame
having a plurality of openings, a vertically
30 movable support mounted in the sliding
frame, a plurality of skittles normally sup-
ported on the track, flexible connections be-
tween the skittles and the vertically movable

support, means for guiding the vertically
movable support in the frame, means for 35
elevating the vertically movable support and
drawing the skittles into the openings and
subsequently moving the sliding frame for-
ward, to position the skittles, the latter fall-
ing from the openings by gravity and sim- 40
taneously lowering the vertically movable
support, and means for returning the slide-
ing frame to normal position.

4. In a game apparatus, the combination
of a frame provided with a track, horizontal 45
guides at the rear of the frame, a frame
slidably mounted in the horizontal guides, a
plurality of skittles adapted to be supported
on the track, a vertically movable support
mounted in the sliding frame, flexible 50
connections between the skittles and the verti-
cally movable support, a guide on the slide-
able frame, a flexible connection attached to
the vertically movable support and passing
over the guide to raise the latter and the 55
skittles and to draw the sliding frame for-
wardly, a second guide, a rope attached to
the rear of the slideable frame, and passing
over the second mentioned guide, and a
weight at the end of the rope to return the 60
sliding frame to normal position, the skittles
and the vertical support falling by gravity
when the flexible connection is released.

In testimony whereof I have hereunto set
my hand.

LÉON FERON.
